**TELEVISION DISPLAY APPARATUS PROVIDED
WITH A CIRCUIT ARRANGEMENT FOR
GENERATING A SAWTOOTH CURRENT
THROUGH A LINE DEFLECTION COIL**

The invention relates to television display apparatus provided with a circuit arrangement for generating a sawtooth current through a line deflection coil forming part of a resonant network also including a trace capacitor and a retrace capacitor, switching means for applying the voltage across the trace capacitor to the deflection coil at the line frequency during the trace time of the sawtooth current, said switching means being blocked during the retrace time, a first current loop comprising a winding of an inductive element and a controllable switch for supplying energy originating from a direct voltage source to the inductive element during the conduction period of the switch and a second current loop comprising a diode and a winding of said inductive element which is connected through the diode to the resonant network, and a field deflection current generator.

Such a circuit arrangement is described in the publication "IEEE Transactions on Broadcast and Television Receivers", August 1972, volume BTR-18, No. 3, pages 177 to 182, and is the combination of a line deflection circuit and a switched supply voltage stabilising circuit in which a single controlled switch serves for fulfilling the two said functions. The circuit arrangement has the advantage that it can be fed with an unstabilised supply voltage and can supply a satisfactorily stabilised sawtooth current and a stabilised high voltage and possible auxiliary voltages. In the known circuit arrangement this stabilisation is obtained by applying the voltage across the trace capacitor as a control voltage to a driver circuit which supplies the switching pulses for the controllable switch (for example, a transistor) and which controls the conduction period of the switch under the influence of this control voltage.

Due to this stabilisation the known circuit arrangement cannot be used without any difficulty in arrangements, for example, colour television display apparatus in which the line deflection must undergo a so-called east-west modulation for correcting the raster distortion. It is possible to control the driver circuit with a field frequency varying signal in such a manner that the deflection current is modulated but this also results in an unwanted modulation of the high voltage and other auxiliary voltages generated with the aid of the circuit arrangement. The above-mentioned publication states that a possible solution is formed by the combination with a known modulator or with a separate EHT generator. As is known, in the first case the modulator and the circuit arrangement must form part of a bridge circuit and in the second case the said generator must be decoupled relative to the circuit arrangement. Alternatively, an EHT generator which is completely separated from the circuit arrangement can be used.

The said solutions lead to more or less complicated and hence costly combinations. It is an object of the present invention to provide a circuit arrangement which is very simple in which east-west modulation of the deflection current is possible without the high voltage and auxiliary supply voltages derived therefrom undergoing this modulation, while both the deflection current and the high voltage and the auxiliary supply voltages are stabilised against fluctuations of the supply

voltage which is generally derived from the electric mains. The circuit arrangement according to the invention maintains the important advantage of the known arrangement, viz. that both the line deflection and the supply voltage stabilisation include one and the same switch. To realize the abovementioned advantages the circuit arrangement according to the invention is characterized in that a modulation source controlled by the field deflection current generator is incorporated in the second current loop for modulating the amplitude of the sawtooth current, the circuit arrangement furthermore including a stabilising circuit for maintaining the amplitude of the voltage occurring across the inductive element during the retrace time of the sawtooth current substantially constant by varying the conduction period of the switch.

In order to maintain the energy dissipated in the modulation source or to be supplied by this source sufficiently low and also to prevent the field frequency east-west modulation from covering a too large part of the admitted variation range of the conduction period of the controllable switch, the television display apparatus according to the invention is preferably furthermore characterized in that the said modulation source provides a line frequency voltage with line flyback pulses which are varied in amplitude in accordance with the field frequency.

The invention will further be described with reference to the Figures shown in the drawing.

30 FIG. 1 shows a first embodiment of a television display apparatus according to the invention,

FIG. 2 shows some voltage and current curves to explain the operation of the embodiment of FIG. 1 and

35 FIGS. 3 to 10 show other embodiments of circuit arrangements in a television display apparatus according to the invention.

The television display apparatus of FIG. 1 includes an RF tuner 1 for connection to an aerial 2, an IF amplifier 3, a detector 4 and a video amplifier with a color decoder 5 applying the color signals to a color display tube 6. This tube has a final anode 7 and is provided with a coil L_y for the horizontal (line frequency) deflection and with a coil L'_y for the vertical (field frequency) deflection.

45 Line synchronizing pulses which are applied to a line oscillator 9 and field synchronizing pulses applied to a field oscillator 10 are separated with the aid of a sync separator 8 from the output signal from detector 4. Oscillator 10 controls a field output stage 11 supplying the deflection current for the coil L'_y . Line oscillator 9 controls a driver stage D_r supplying switching pulses for a switching transistor T_r of a line deflection output circuit to be further described.

55 A trace capacitor C_1 is arranged in series with line deflection coil L_y and a diode D_1 having the given conductivity direction and a retrace capacitor C_2 are connected in parallel with the series arrangement thus formed. The retrace capacitor C_2 may alternatively be arranged in parallel across coil L_y . The said four elements only show the principle circuit diagram with the main components of the deflection section. This section may be provided, for example, in known manner with one or more transformers for mutual coupling of the elements, with circuits for centering and linearity correction and the like.

A secondary winding L_2 of a transformer A is in series with a diode D_3 whose cathode is connected to the

junction of elements D_1 , C_2 and L_y and to the anode of a diode D_2 . The cathode of diode D_2 is connected to one end of a primary winding L_1 of transformer A and to the collector of transistor T_r which is of the npn type. The positive terminal of a direct voltage source B is connected to the other end of winding L_1 and the negative terminal is connected to ground. The free ends of elements D_1 , C_2 , C_1 and the emitter electrode of transistor T_r are also connected to ground.

A further winding L_3 is wound on the core of transformer A one end of which is connected to ground while the other end is connected to the anode of a rectifier D_4 whose cathode is connected to earth through a capacitor C_3 . The output voltage of rectifier D_4 is applied to driver circuit D_r for controlling the conduction period of the transistor T_r . Windings L_1 and L_2 preferably have the same number of turns. The winding sense of the transformer windings is denoted by polarity dots in the Figure.

A modulation source M is included between the end of winding L_2 remote from diode D_3 and ground. This modulation source includes an emitter follower transistor T_r' arranged between said end of winding L_2 and ground and a capacitor C_4 connected in parallel across its emitter-collector path as well as a driver stage D_r' controlling the base electrode of transistor T_r' which stage is connected to the field output stage 11. Driver stage D_r' generates a field frequency parabolically varying modulation voltage v_M from the signals of the field output stage and this voltage is also active through emitter follower T_r' at the low side of winding L_2 .

Modulation voltage v_M serves for the east-west raster correction of the line deflection current. Voltage v_M varies in accordance with the field frequency but may be considered as a constant voltage during a line period. Since the raster distortion to be corrected is generally pin-cushion shaped, it is known that the introduced modulation must be such that the amplitude of the line deflection current varies with a parabolic envelope with the peak of the parabola occurring in the middle of the field scan time and coinciding with the maximum amplitude.

Further windings are wound on the core of transformer A across which there are voltages which serve as supply voltages for other parts of the television display apparatus. One of these windings, winding L_4 , is shown in FIG. 1 and generates the EHT for the final anode 7 of television display tube 6 with the aid of an EHT rectifier D_5 across a smoothing capacitance C_5 . The supply voltages thus obtained as well as the EHT must not undergo the same field frequency modulation as the line deflection current. In addition, like this current, they must be stabilised against fluctuations of the voltage V_B of source B generally derived from the electric mains. Both requirements are satisfied in accordance with the invention because the voltage across capacitor C_3 which is obtained by peak rectification of the flyback pulses present across winding L_3 is applied to driver circuit D_r . Driver D_r includes a comparison stage and a modulator which ensure in known manner that the conduction period of transistor T_r is varied.

The operation of the circuit arrangement of FIG. 1 will be explained with reference to the curves of FIG. 2. In FIG. 2a the voltage v_2 across capacitor C_2 , in FIG. 2b the voltage v_L across winding L_2 and in FIG. 2c the current i_1 through winding L_1 and the current i_2 through winding L_2 are plotted as a function of time with T de-

noting the line period. The retrace time is denoted by t_r while $(1 - \delta) t_r$ denotes the part of the trace time t_r during which transistor T_r is cut off and δt_r denotes the part where transistor T_r conducts. As will be apparent the number δ is to be between 0.5 and 1.

After the commencement t_0 of the trace diode D_1 conducts. The voltage across capacitor C_1 is applied to deflection coil L_y so that a sawtooth deflection current flows through this coil. When the deflection current reverses its direction approximately in the middle of trace t_r , diode D_1 is blocked but in this case the deflection current flows through diode D_2 and the then conducting transistor T_r . Since the polarity of the deflection current is reversed approximately in the middle of trace t_r and since it must be possible for the deflection current to flow unhampered through transistor T_r during the second half of the trace, it will be evident that the instant t_1 when the transistor is rendered conducting is to be before the middle of the trace. This means that δ must be more than 0.5.

At the end t_2 of the trace transistor T_r is cut off. A sinusoidal flyback voltage is produced across capacitor C_2 . At an instant t_0' the voltage v_2 becomes zero again so that diode D_1 is rendered conducting: this is the commencement of a new trace.

During the part δt_r of the trace when transistor T_r is conducting, a linearly increasing current i_1 flows through winding L_1 . Thus current i_1 flows through transistor T_r as well as the deflection current which flows via diode D_2 after the deflection current has reversed its direction. When at the instant t_2 transistor T_r is cut off not only the current path for the deflection current but also that for current i_1 is interrupted. The latter results in a current i_2 flowing in secondary winding L_2 whose initial value (in case of equal numbers of turns between L_1 and L_2) is equal to the final value of i_1 . The current i_2 renders diode D_3 conducting against the flyback pulse v_2 then occurring at the cathode of diode D_3 . As a result the flyback pulse appears on the high side of winding L_2 and magnetically also on the low side of winding L_1 , at the collector of transistor T_r and at the cathode of diode D_2 which is blocked thereby.

Also after the instant t_0 when the retrace ends diode D_3 remains conducting until transistor T_r is rendered conducting; current i_2 becomes zero and current i_1 starts to flow.

When V_0 is the direct voltage across capacitor C_1 if this has a sufficiently large capacitance or when it is the direct voltage component of the voltage across capacitor C_1 if this has a relatively low capacitance for the S-correction, then V_0 is equal to the mean value of v_2 . In fact no direct voltage component can be present across coil L_y . There applies:

55

$$V_0 = \frac{1}{T} \int_0^{t_r} v_2 dt$$

60 Voltage v_{L_2} is equal to the difference between the voltage at the anode of diode D_3 and modulation voltage V_M . During the interval between t_0 and t_1 the former voltage is zero (diodes D_3 and D_1 conduct) so that $v_{L_2} = -v_M$ so that the current i_2 is sawtooth-shaped while

65

$$v_M = L \frac{di_2}{dt}^2$$

with L = the inductance of the transformer on windings L_1 and L_2 . During retrace t_r the anode voltage of diode D_3 is equal to voltage v_2 because diode D_3 conducts so that $v_L = v_2 - v_M$ while current i_2 is given by

$$v_2 - v_M = -L \frac{di_2}{dt}$$

During the interval between t_1 and t_2 the collector voltage of transistor T_r is zero so that voltage V_B prevails across winding L_1 and hence across winding L_2 . This voltage may be considered constant during a line period. In this interval the sawtooth current i_1 flows through the winding L_1 in which

$$V_B = L \frac{di_1}{dt}$$

The mean value of voltage v_{L_2} , i.e. the voltage across an inductor, must be zero. The surface in FIG. 2 shaded to the right must thus be equal to the surface shaded to the left so that there applies:

$$v_M(1 - \delta) t_1 + v_B \delta t_1 \approx \int_0^{t_r} v_2 dt - v_M t_r$$

In this formula V_o can be filled in:

$$V_o T = V_B \delta t_1 + v_M(T - \delta t_1)$$

10

and

$$v_K = 10 V_o - v_M$$

The mean value of voltages V_B and V_o are 290 V and 143 V, respectively. When the control of driver D_r is adjusted by the voltage across C_3 in such a manner that the number δ is in the middle of its variation range, i.e. $\delta = 0.75$, there follows from formula (2) that the mean value of $v_M = -118$ V and from formula (3):

20

$$v_K = 10 V_o - v_M = 1548 \text{ V.}$$

(4)

The other values of v_M and δ can be calculated with the aid of formulas (2) and (4). At the extreme values of V_B and v_M we find:

$$V_B = 340 \text{ V}$$

$$V_o = 148 \text{ V}$$

$$v_M = -68 \text{ V}$$

30 $\delta = 0,62$

and

$$V_B = 240 \text{ V}$$

$$V_o = 138 \text{ V}$$

$$v_M = -168 \text{ V}$$

35 $\delta = 0,88$

and

$$V_B = 240 \text{ V}$$

$$V_o = 138 \text{ V}$$

$$v_M = -168 \text{ V}$$

35 $\delta = 0,88$

Since the number δ remains within the admissible limits, i.e. 0.5 and 1 it is found that the circuit arrangement of FIG. 1 can be realized for the given variations of voltages V_B and V_o . It is also found that voltage v_M must always be negative so that the straight piece of the line between the instants t_0 and t_1 in FIG. 2b is located above the time axis while current i_2 in FIG. 2c will linearly decrease between the same instants.

In practice source M may be formed as a passive element. In fact, the current i_2 flowing through this element produces a negative voltage drop thereacross. Such an element may be a field frequency varying resistor, for example, formed as a controlled transistor. However, since current i_2 depends on the number δ and hence on voltage V_B , source M must have a low internal resistance so that voltage v_M cannot be influenced by voltage V_B . Such a source is, for example, the transistor T_r' arranged as an emitter follower which receives a field frequency parabola signal through the control circuit D_r' in such a manner that the voltage at the junction of winding L_2 and transistor T_r' is always negative relative to the earth potential and that the peak of the parabola in the middle of the field scan time is less negative than the values at the commencement and at the end of this time. A capacitor C_4 bypasses the said junction for line frequency signals.

It will be evident that in the arrangement of FIG. 1 diode D_1 may be replaced in known manner by the parallel arrangement of a transistor and a diode, in which the transistor must be line-frequency controlled, for example, by driver circuit D_r and in which diode D_2 can be omitted. It is obvious that the operation remains the

$$z = \frac{t_r}{T}$$

is proportional to the amplitude v_{2max} of voltage v_2 , it follows from the foregoing that voltage V_o and hence the amplitude of the deflection current varies with the variation of voltage v_M which is desirable. On the other hand variations of supply voltage V_B do not have any influence on voltage V_o . Formula (1) shows that the variation of the number δ accounts for both that of voltage V_B and that of v_M . The amplitude v_K always remains constant independent of the variations in the voltages V_B and v_M . The same applies to the amplitudes of the voltages across winding L_4 and across the other windings (not shown) of transformer A. The EHT and the auxiliary supply voltages obtained in a corresponding manner are therefore not east-west modulated and

same. This also applies to the embodiments which will now be described.

Possible modifications of the known circuit arrangement are described in Netherlands Pat. application No. 7217254 (PHN 6677). Similar modifications are also possible with those of FIG. 1. In FIGS. 3 and 4 two of these modifications are shown in which the same reference numerals have been used for the same elements as in FIG. 1 and in which windings L_1 and L_2 are replaced by one winding L' . As described in the said Netherlands patent application these modifications have the advantage that a leakage inductance of the transformer A cannot have a detrimental influence. In FIG. 4 a capacitor C_B operates as a supply voltage source whose charge is repleted through a choke L_B from direct voltage source B.

FIG. 5 shows an embodiment of the circuit arrangement according to the invention which has a similar operation as that of FIG. 1 with the difference that voltage v_{L_2} between instants t_1 and t_2 is not equal to $-V_B$ but to $-(V_B + v_M)$. Similar formulas as those above may be derived explaining the variation of the number δ in case of variation of voltages v_B and v_M .

FIGS. 6 and 7 show modifications of the embodiment according to FIG. 5 which modifications are derived in the same manner from FIG. 5 as those of FIG. 3 and FIG. 4 are derived from FIG. 1.

It is to be noted that in all modifications modulation source M forms part of a current loop which comprises windings L_2 and L' and diode D_3 and which is closed through the deflection section D_1 , C_2 , L_y , C_1 . In the modifications of FIGS. 4, 5, 6 and 7 modulation source M also forms part of the current loop comprising windings L_1 and L' and transistor T_4 and which is closed through direct voltage source B and the capacitor C_B operating as a direct voltage source, respectively.

Since only the amplitude of the voltage across winding L_3 is maintained constant during the line flyback time it is only sufficient, according to a further aspect of the invention, to choose a field frequency varying voltage for the voltage v_M which voltage occurs only during the said line retrace. Even a part thereof, namely just before and after the middle of the line retrace is sufficient. When in addition voltage v_M is zero in the interval between t_0 and t_1 the power dissipated or supplied by the modulation source is also zero during this interval. The value of voltage v_M in the interval between t_1 and t_2 is less important because diode D_3 is then blocked. A further advantage is that the variation of the number δ caused by the east-west modulation is slighter which has been proved in practice.

An embodiment of this principle is shown in FIG. 8. The modulation source now includes an extra transformer winding L_5 which applies negatively directed flyback pulses through the control circuit D_r' to the emitter follower transistor T_r' . In control circuit D_r' the attenuation or amplification of the flyback pulses is field frequency parabolically varied by means of the control from field output stage 11. The modulation voltage v_M on the low side of winding L_2 thus consists of field frequency amplitude varying line flyback pulses causing the east-west modulation of the line deflection current. The positive voltage on the low side of winding L_5 during the time between t_1 and t_2 has no influence on the modulation voltage because then transistor T_r' is saturated. During the entire line scan time modulation voltage v_M is therefore equal to zero so that transis-

tor T_r' does not dissipate energy during this time. It can be proved that in this embodiment the conduction period (δ) of the transistor T_r is only varied by supply voltage (V_B) variations and not by variations of the modulation voltage v_M . Instead of being derived from a transformer winding the flyback pulses for the control circuit D_r' may alternatively be derived from the retrace capacitor C_2 .

FIG. 9 shows another embodiment based on the same principle. The modulation source M of FIG. 4 is constituted in FIG. 9 by a coil L_6 whose inductance varies with the field frequency and parabolically. Such a coil is known and may be formed as a power winding of a saturable reactor whose control winding receives a field frequency current. A voltage is present across coil L_6 which voltage is a field frequency varying fraction of the voltage across the series arrangement of L_6 and L' . The latter voltage is equal to voltage v_2 during the retrace and in the interval between t_0 and t_1 this voltage is equal to zero and in the interval between t_1 and t_2 it is equal to the voltage $-V_B$ of capacitor C_B . The energy applied by inductor L_6 to the deflection section through D_3 during the retrace is repleted again from capacitor C_B during the interval between t_1 and t_2 . In the modulation method of FIG. 9 modulation source L_6 thus dissipates nothing except for the energy required for the control of this source.

Another embodiment is shown in FIG. 10. Diode D_3 is displaced to the low side of winding L_2 and an additional transformer winding L_7 with considerably fewer turns than winding L_2 is arranged between diode D_3 and modulation source M. The cathode of a further diode D_3' is connected to the cathode of diode D_3 and its anode is connected to earth. Modulation source M supplies a negative parabola field frequency varying direct voltage so that only the peaks of the flyback pulses across winding L_7 cause diode D_3 to conduct. Modulation source M thus is only active during these peaks in the current loop L_7 , D_3 , L_2 and the deflection section D_1 , C_2 , L_y , C_1 and only during these peaks does source M supply or dissipate energy. During the other part of the retrace and during the interval between t_0 and t_1 of the trace diode D_3' is conducting and takes over the normal function of D_3 of FIG. 1. Diodes D_3 and D_3' are both blocked during the conducting period between t_1 and t_2 of transistor T_r .

What is claimed is:

1. Television display apparatus provided with a circuit arrangement for generating a sawtooth current through a line deflection coil forming part of a resonant network also including a trace capacitor and a retrace capacitor, switching means for applying the voltage across the trace capacitor to the deflection coil at the line frequency during the trace time of the sawtooth current, said switching means being blocked during the retrace time, a first current loop comprising a winding of an inductive element and a controllable switch for supplying energy originating from a direct voltage source to the inductive element during the conduction period of the switch and a second current loop comprising a diode and a winding of said inductive element which is connected through the diode to the resonant network and a field deflection current generator, characterized in that a modulation source controlled by the field deflection current generator is incorporated in the second current loop for modulating the amplitude of the sawtooth current, the circuit arrangement further-

more including a stabilizing circuit for maintaining the amplitude of the voltage occurring across the inductive element during the retrace time of the sawtooth current substantially constant by varying the conduction period of the switch.

2. Television display apparatus as claimed in claim 1, characterized in that the modulation source includes an emitter follower stage incorporated in said second current loop as well as a control device for field frequency controlling the emitter follower stage.

3. Television display apparatus as claimed in claim 1, characterized in that the modulation source supplies a line frequency voltage with line flyback pulses with a field frequency amplitude variation.

4. Television display apparatus as claimed in claim 3, characterized in that the modulation source supplies a line frequency voltage which is substantially zero at least during the part of the line trace time when the controllable switch is blocked.

5. Television display apparatus as claimed in claim 2 and characterized in that the modulation source supplies a line frequency voltage with line flyback pulses with a field frequency amplitude variation and line flyback pulses originating from a winding of the inductive element control the emitter follower stage through a field frequency amplification-controlled control circuit.

6. Television display apparatus as claimed in claim 3, characterized in that the modulation source is constituted by a controllable inductor, for example, the power winding of a saturable reactor.

7. Television display apparatus as claimed in claim 1, characterized by the series arrangement of the modulation source with a winding on the inductive element and with the third diode in which a further diode is

present in parallel across the said series arrangement.

8. Television display apparatus as claimed in claim 1, characterized in that the modulation source is incorporated both in the first and in the second current loop.

5 9. Television display apparatus as claimed in claim 1, characterized in that the switching means consist of a parallel diode and the series arrangement of a series diode and the controllable switch connected in parallel therewith.

10 10. A circuit arrangement for generating a sawtooth current through a line deflection coil, said circuit arrangement comprising a trace capacitor and a retrace capacitor forming a resonant circuit with said coil; switching means for applying the voltage across the trace capacitor to the deflection coil at the line frequency during the trace time of the sawtooth current, said switching means being blocked during the retrace time; a first current loop comprising a winding of an inductive element and a controllable switch means coupled to said element for supplying energy originating from a direct voltage source to the inductive element during the conduction period of the switch; a second current loop comprising, a field deflection current generator, a diode, a winding of said inductive element coupled through the diode to the resonant network and to said field deflection current generator, and a modulation source means controlled by the field deflection current generator for modulating the amplitude of the sawtooth current; and a stabilizing circuit means for maintaining the amplitude of the voltage occurring across the inductive element during the retrace time of the sawtooth current substantially constant by varying the conduction period of the switch.
